UNITED STATES PATENT OFFICE.

MARK THOMAS DENNE, OF RUSHDEN, ENGLAND.

HEEL-SEAT-TRIMMING MACHINE FOR USE IN THE MANUFACTURE OF BOOTS AND SHOES.

1,152,799.

Specification of Letters Patent.

Patented Sept. 7, 1915.

Application filed August 22, 1910. Serial No. 578,397.

To all whom it may concern:

Be it known that I, MARK THOMAS DENNE, a subject of the King of Great Britain and Ireland, residing at Rushden, Northamptonshire, England, have invented new and useful Improvements in Heel-Seat-Trimming Machines for Use in the Manufacture of Boots and Shoes, of which the following is a specification.

10 This invention has reference to improvements in heel seat trimming machines for use in the manufacture of boots and shoes whereby the edge of the sole forming the heel seat may be trimmed at any desired pre-
15 determined distance from the upper or the crease of a lasted boot or shoe, and it consists essentially in a particular construction and arrangement of the trimming mechanism and feed mechanism and a particular
20 arrangement of the presser foot.

In the accompanying drawing Figure 1 is a side elevational view partly in section, Fig. 2 a plan view, Fig. 3 a front elevation of a heel seat trimming machine constructed
25 in accordance with my invention, and Fig. 4 is a detail view hereinafter referred to.

In said drawings the numeral 1 indicates an arcuate trimming knife and 2 a similarly shaped feed awl or feed foot which is located at the side of the knife and preferably slightly to the rear thereof and is adapted to enter or engage the projecting part of the sole to be trimmed.

The knife and feeder are supported in a
35 clamp or cramp 3 of a rocking bar or carrier 4, which clamp has V grooves in which the correspondingly shaped outer edges of said knife and feeder fit. The bar 4 is supported on a spindle 5 on which it is capable
40 of rocking and also sliding axially and its rear end is formed with a *quasi* claw 6 having a cylindrical recess 7 in which a cylindrical block 8 slidably and rotatably fits.

An eccentric or crank pin 9, formed or provided on a shaft 10 for which I provide suitable bearings at the rear of the machine head and on which a triangular cam 9^a and the usual driving and loose pulleys 11 are mounted, enters an aperture in the block 8 so that the rotation of the shaft 10 will rock the lever 4 and consequently impart to the knife 1 and feeder 2 vertical, rocking movements. A sleeve or equivalent 12 formed at each end with upwardly extending arms 13, 55 one of which is bifurcated and engages the

triangular cam 9^a on the shaft 10 and the other of which engages a slot in the boss of the lever 4, is mounted on a rock-shaft 14 located below the lever 4, the position of the crank pin 9 and triangular cam 9^a relatively to each other being such that at each rotation of the shaft 10 the knife and feeder will have imparted to them by the combined action of the crank pin 9 and the triangular cam 9^a a four motion feed movement, the vertical rocking movement being brought about by the action of the crank pin 9 and the horizontal movements by the triangular cam 9^a, the knife during its downward movement severing or cutting through the sole edge. Fig. 4 is a front end view of the said shaft 10, crank pin 9 and cam 9^a.

The work is supported with its sole or heel seat substantially horizontal by a table 15 at the front of the head and also by a roller hereinafter referred to. A gage 16, whose front end is shaped to approximately conform to the shape of the heel portion of the lasted boot, the sole or heel seat of which is to be trimmed, is adjustably carried by an approximately inverted U-shaped saddle piece 17 which is supported on the spindle 5. The bottom edge or surface of the gage 16 is intended to engage with the upper surface of the projecting sole edge and act as a presser foot, the saddle piece 17 being pressed forwardly—so that the presser foot exerts the necessary pressure on the sole edge—by a spring 18 arranged within a suitable housing and acting on a plunger 19 pivotally connected to the saddle 17. The said presser foot presses the sole edge into firm contact with a roller 20 the periphery of which projects up into an aperture in the table 15 and may with advantage be formed with teeth or serrations to insure a better grip.

The saddle piece 17 is provided with a handle 17^a by pressing on which the workman may raise the presser foot when about to insert or remove work.

The parts are so arranged that the acting surface of the presser foot is substantially in horizontal alignment with the axis of the spindle 5 on which it turns and accordingly the pressure which the workman exerts in pressing the lasted boot against the gage or presser foot 16 has no tendency to raise the said presser-foot.

At the front of the machine head and im-

mediately behind the roller 20 I provide a preferably circular shear blade 21 to serve in conjunction with the cutter 1 in shearing off the edge of the sole. The shear blade 21 may from time to time be moved on its support so as to offer a fresh shearing edge accordingly as wear takes place.

The roller 20 is preferably supported on the rock-shaft 14 and the front end of said shaft may have a ratchet ring 22 mounted on it the teeth of which engage with corresponding teeth on the roller 20. The ratchet ring 22 is made to rotate or rock with the shaft 14 being coupled thereto by a cotter 23 but is capable of endwise movement thereon and is pressed against the roller 20 by a spring the arrangement being such that when the rock-shaft is moved in one direction by the triangular cam 9^a the ratchet ring 22 will rotate the roller 20 with it and thus feed the work, and on the return movement of the shaft 14 the ratchet ring 22 will glide over the teeth of the roller 20.

If desired, the shear blade 21 may be fixed 25 to the roller 20 so that at each feed movement of said roller the shear will be made to present a fresh cutting edge.

The gage 16 may at its lower edges be made to enter the crease to serve as a crease 30 guide, and as the work is fed by the roller 20 and the feeder the operator will move the work so as to properly present it to the cutters.

The numeral 24 indicates the head of the 35 machine of suitable construction to carry the mechanism, and 25 is the usual standard which supports the said head.

What I claim as my invention and desire 40 to secure by Letters Patent is:—

1. In a machine for trimming the projecting edge of the heel seat of lasted boots and shoes, the combination of a work support, a curved trimming knife, a curved feeder, a 45 rocking lever on which the said knife and feeder are mounted, a shaft on which the said lever is mounted so that it can rock and slide thereon, and means comprising a rotating crank pin and a triangular cam for imparting a four-motion movement to the 50 said rocking lever.

2. In a machine for trimming the projecting edge of the heel seat of lasted boots and shoes, the combination of a work table, a feed roller let into an aperture in the said 55 table, means for intermittently rotating the said roller, a curved trimming knife, a curved feeder, means for imparting a simultaneous four-motion movement to the said

knife and feeder, and a combined presser-foot and gage supported on a horizontal 60 spindle the axis of which is in approximately the same horizontal plane as the acting face of the said presser-foot.

3. In a machine for trimming the projecting edge of the heel seat of lasted boots or 65 shoes, the combination of a work table, an arcuate trimming knife and an arcuate work feed-foot, a rocking lever supported on a horizontal spindle to carry said knife and feed foot at its front end and having a claw 70 with a cylindrical recess at its other end, a cylindrical block in said recess, means to impart simultaneous vertical and horizontal movements to said block and means to impart axial movements to the rocking lever. 75

4. In a machine for trimming the projecting edge of the heel seat of lasted boots or 80 shoes, the combination of a work-table, a work feed wheel, means for intermittently rotating said work feed wheel, a trimming 85 knife, a spring pressed presser foot to engage the upper face of the sole near its edge and also to limit the movement of the work toward the knife, a saddle to carry said presser foot and a spindle whose axis is in 90 substantially the plane of the table to carry said saddle.

5. In a machine for trimming the projecting edge of the heel seat of lasted boots or 95 shoes, the combination of a work table, a trimming knife, a stationary shear blade located in a slot in the said table and adapted to coöperate with the said knife, and a spring-pressed presser foot pivotally mounted on a spindle the axis of which is in approximately the same horizontal plane as 100 the acting face of the said presser foot.

6. In a machine for trimming the projecting edge of the heel-seat of lasted boots or 105 shoes, the combination of a work-table, an intermittently rotatable work feed wheel, an arcuate trimming knife, a stationary shear blade adjustably mounted below the surface of the work-table and adapted to co-operate with the said knife, a rocking lever 110 to carry the said trimming knife, a combined presser foot and work gage, and means to impart four-motion movement to said rocking lever.

In testimony whereof I have signed my 110 name to this specification in the presence of two subscribing witnesses.

MARK THOMAS DENNE.
